UNITED STATES PATENT OFFICE.

CHARLES V. KERR, OF WELLSVILLE, NEW YORK, ASSIGNOR TO McEWEN BROS., OF WELLSVILLE, NEW YORK.

BLOWER.

1,080,763.

Specification of Letters Patent. Patented Dec. 9, 1913.

Application filed December 14, 1911. Serial No. 665,785.

To all whom it may concern:

Be it known that I, CHARLES V. KERR, a citizen of the United States, and a resident of Wellsville, New York, have invented certain new and useful Improvements in Blowers, of which the following is a specification.

My invention relates to a blower of the propeller type, specially adapted for supplying air under pressure to furnaces, although it may be used for other purposes.

More particularly, my invention comprises two impellers of the disk type arranged to work toward each other and usually mounted on a single shaft, in combination with a suitable deflector and a volute casing.

Further, the invention consists in specially shaping the blades of the impellers to coöperate with the other features of the invention to best advantage.

Further, I provide a novel form of bearing for the impeller shaft comprising a stuffing box which prevents atomizing and waste of oil supplied to the bearing.

I will now describe my invention in detail with reference to the accompanying drawing which illustrates exemplifying structures in which the invention is embodied.

Figure 1 is a vertical section of one form of the invention. Fig. 2 is an enlarged sectional view of one of the bearings. Fig. 3 is a vertical section of another form of the invention. Fig. 4 is an enlarged detail of the shaft, impellers, and deflector. Fig. 5 is an enlarged front view of one of the blades. Fig. 6 is a side view of the same. Fig. 7 is a section of the blade near the tip. Fig. 8 is a section of the blade near the base. Fig. 9 is an end elevation of the form of blower shown in Fig. 1. Fig. 10 is an end elevation of the blower shown in Fig. 3. Fig. 11 is a sectional detail of a modified form of deflector shown in proper relation to the shaft and impellers; and Fig. 12 is still another modification of the deflector.

Referring first to Figs. 1 and 9, reference character 1 designates the shaft, carrying impeller hubs 2 on which blades 3 are mounted. These blades may be secured in the manner fully described in my prior pending application, Serial #648,584, filed September 9, 1911, and the blades may also be formed as described in said application and as illustrated in Figs. 5 to 8 inclusive, in

which it appears that while the blades near the tip have a moderate pitch angle in the direction of rotation, this angle proportionately increases toward the base as shown in Fig. 8, where the angle is very abrupt, so that at all portions of their length the blades have an impelling capacity suited to their angular velocity at that point. The blades as shown in Figs. 7 and 8 have curved impelling faces and in the preferred form this curvature increases from the tip toward the base of the blade. The important shape of these blades may be graphically described by saying that the blades have curved impelling faces and that the average pitch-angle of the blades with relation to the plane of rotation increases from the tip toward the base. The average angle may, of course, be indicated by a straight line drawn from one edge of the blade to the other in planes parallel to the planes indicated in Figs. 7 and 8. More particularly, the shape of the blades may be described by saying that they have curved impelling faces, the curvature increasing from the tip toward the base, the average pitch angle also increasing from tip toward the base. This form of blade when the curvatures uniformly increase from tip to base and angle correspondingly increases, may mathematically be described as an increasing helicoidal pitch. This mathematical term, however, is not employed in the claims because the change in curvature and pitch angle may be not absolutely uniform, and, therefore, not exactly in accordance with the mathematical definition, while the blades may still come within the spirit of the invention as described by the graphic phrases above. The shaft 1 is supported in bearings carried by the boxes 4. 5 designates in general the impeller casing, of which the periphery 6, as shown in Fig. 9, is of volute form. The casing terminates at 7 in a discharge opening. The casing is provided at each side adjacent to one of the impellers with a flared mouth or supply passage 8. The tips of the blades revolve close to the throats 9 of these supply passages. Struts 10 support bearing boxes 4. Surrounding the shaft, between the two impellers, is a deflector designated generally by reference character 11. The form of this deflector may vary greatly. As shown in Fig. 1 an approved form consists of a double conoid of which the small ends are se-

cured to the hubs and the large ends meet to form an annulus 12 centrally located within the casing. When the shaft is revolved at suitable speed, the disk impellers 5 with blades peculiarly shaped, as described in my aforesaid application, take air through the supply ports 8 and deliver it at high velocity into the casing. The impelled air leaving the inner edges of the blades takes 10 a diagonal path inward, forward (in the direction of shaft rotation) and outward, and the volute casing effectively accommodates the air entering in this manner and efficiently converts the kinetic energy of the 15 fluid into static energy or pressure. The deflector 11 serves effectively, by reason of its form and arrangement, to prevent eddy currents which otherwise tend to form within the casing.

20 A blower constructed as described will very efficiently develop satisfactory pressure for supplying air for combustion to furnaces, etc.

In blowers and exhaust fans heretofore 25 constructed, it has been found that the entering air and the rapid rotation of the shaft tend to atomize oil in the bearings and to rapidly dissipate and waste the lubricant. To prevent this I provide my bearing boxes 30 4, as shown in Fig. 2, with stuffing glands 15 secured by screws 16. By means of these stuffing boxes and packing 17, the shaft bearings toward the impellers may be made satisfactorily oil-tight and waste of oil may be 35 prevented. The details of the bearing proper may vary greatly but the described construction operates satisfactorily in connection with ring oiling bearings as illustrated.

It has been stated that the form of the deflector 40 may be varied greatly. Fig. 11 shows a deflector consisting of a hollow cylinder 30 placed between the impeller hubs and to this may be added a central disk 31. The cylinder 30 forms in effect an enlargement of the 45 shaft and takes up eddy space that would otherwise be present, and the disk 31 also forms a baffle which prevents eddy currents.

Instead of the conoidal deflector shown in 50 Fig. 1, a deflector 35 of double straight conical form, as shown in Fig. 12, may be employed. Further, the size of the central portions of the deflectors, in any of these forms, and the consequent angle of the cones, or other dimensions, may be considerably varied.

Fig. 3 shows a modification of the blower construction in which an annular throat or nozzle 40 is placed between the casing 5 and the discharge chamber 41 adjacent to the 55 deflector. This form of the blower is efficient and desirable in some cases.

I claim:

1. In a blower, the combination of a volute 60 casing, a shaft therein, a disk impeller on the shaft, a deflector at the discharge side of the

impeller, a bearing for the shaft at the suction side of the impeller, and a stuffing box for the bearing about the shaft to prevent oil loss due to fan suction.

2. In a blower, the combination of a volute 70 casing, a shaft therein, two disk impellers on the shaft arranged to discharge toward each other, and a deflector between the impellers, bearings for the shaft outside the impellers and stuffing boxes for the bearings 75 about the shaft to prevent oil loss due to fan suction.

3. In a blower, the combination of a volute 80 casing, a shaft, two disk impellers on the shaft, one at each side of the casing, each impeller comprising a hub and blades, said blades having curved faces, the average pitch-angle of the blades with relation to the plane of rotation increasing from the tip toward the base, and a deflector within the 85 casing about the shaft between the impeller hubs.

4. In a blower, the combination of a volute 90 casing, a shaft, two disk form impellers on the shaft, one near each side of the casing, the casing being provided with opposite inlet openings leading to said impellers, and a double conoidal deflector within the casing 95 and about the shaft between the impellers, the conoid bases adjoining each other centrally within the casing.

5. The combination of a volute casing, a shaft therethrough, a deflector thereon centered in the casing, the casing being provided with annular air inlets one at each side, disk 100 impellers on said shaft one within each of the inlets and working toward the center, the blades of said impellers having curved working faces, the curvature of the faces increasing from the tip toward the base and 105 the average pitch-angle of the blades also increasing from the tip toward the base of the blades.

6. In a blower, the combination of a volute 110 casing, a shaft, disk impellers comprising a hub and blades, said blades having curved working faces, the curvature of said faces increasing from the tip toward the base of the blades, the average pitch angle of the blades to the plane of rotation also increasing from 115 the tip toward the base of the blades.

7. In a blower, the combination of a rotatable shaft, a discharge casing of volute form in a plane perpendicular to the shaft, the sides of the casing being provided with circular air inlets concentric with the shaft, two disk impellers on the shaft, one within each of said air inlets, the impellers being arranged to discharge toward each other, and a deflector within the casing between the impellers. 120

8. In a blower, the combination of a rotatable shaft, a discharge casing of volute form in a plane perpendicular to the shaft, the sides of the casing being provided with cir- 125

cular air inlets concentric with the shaft, two disk impellers on the shaft, one within each of said air inlets, the impellers being arranged to discharge toward each other, each impeller comprising a hub and blades, said blades having concaved working faces of helical pitch, said pitch increasing at all points of the blade from the inlet to the discharge edges to obtain an increased discharge head, and a deflector within the casing between the impellers. 10
